Primary Examiner — Deanna L Fluegeman*(74) Attorney, Agent, or Firm* — Foley & Lardner LLP(57) **CLAIM**

The ornamental design for scissor handles, as shown and described.

DESCRIPTION

FIG. 1 is a first isometric view of a first embodiment of the claimed design;

FIG. 2 is a second isometric view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a first isometric view of a second embodiment of the claimed design;

FIG. 10 is a second isometric view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines in the drawings illustrate the environment of the claimed design and form no part of thereof.
